UNITED STATES PATENT OFFICE.

GEORGE J. CLINE, OF GOSHEN, INDIANA, ASSIGNOR, BY DIRECT AND MESNE ASSIGNMENTS, TO L. H. NOBLE AND J. M. NOBLE, BOTH OF SAME PLACE.

BRUSH-HANDLE ATTACHMENT.

SPECIFICATION forming part of Letters Patent No. 368,070, dated August 9, 1887.

Application filed January 6, 1887. Serial No. 223,518. (No model.)

To all whom it may concern:

Be it known that I, GEORGE J. CLINE, a citizen of the United States, and a resident of Goshen, in the county of Elkhart and State of Indiana, have invented certain new and useful Improvements in Brush-Handle Attachments; and I do declare the following to be a full, clear, and exact description of the invention, such as will enable others skilled in the art to 5 to which it appertains to make and use the same, reference being had to the accompanying drawings, and to letters or figures of reference marked thereon, which form a part of this specification.

15 Figure 1 of the drawings is a representation of my invention and is a perspective view of the same. Fig. 2 is a vertical longitudinal section. Fig. 3 is a top view with the brush-handle removed, and Figs. 4 and 5 are detail 20 views.

My invention relates to brush-handle attachments for scrubbing-brushes and the like; and it consists in the construction and novel combination of parts, as hereinafter set forth.

25 Referring by letter to the accompanying drawings, A designates the body of the brush, in which the bristles are secured in any of the ways commonly practiced in the manufacture of brushes.

30 B is the covering for the back of the brush-body proper, said covering being secured to the brush-body A by nails or screws.

C and D are shouldered plates, which are rigidly secured to the brush-plate B.

35 E is a button, which has a shoulder, F, on one end, and in other respects is similar to an ordinary thumb-nut, except that its eye is not threaded. This button is secured in place by a screw, G, upon which it is turned to move it 40 into the locked or unlocked positions.

H is a metal disk, which is provided with an upwardly-projecting stud, I, said stud I having an eye, K, made transversely through it near its upper end.

45 L designates a tang, which is secured in a seat or socket in the lower end of the brush-handle by a rivet passed transversely through the handle and through an eye or perforation in the upper end of the tang. The tang L is 50 slightly enlarged at its lower end, and is provided with projecting lugs M M, between which the upper end of the stud I is hinged upon a pivot-bolt, N, having its bearings in the

lugs M M. This pivot-bolt N is headed at one end, and the other end projects to receive a 55 securing-nut, P, by which it is retained in its seat to provide the joint Q, by which the handle is permitted to be turned to the desired angle with relation to the brush to enable the operator to use the brush without being required to kneel or to assume unnecessarily-tiring positions in operating the brush. By this means of arranging the shouldered plates and the shouldered button on the brush-plate B the brush-handle may be readily attached and 60 detached. The handle may be also turned to cause the disk to describe a circle or part of a circle by simply turning the button out of engagement with the disk while the handle is in a vertical position, or in a horizontal position, 65 or while the handle is in any position intermediate of the vertical and horizontal positions. In fact, the latitude of adjustment given to the handle by this construction is such as to permit the brush to be used in almost any required position. After the adjustment has been made the button is again turned into engagement with the disk. Furthermore, the handle and disk attachment may be removed by simply turning the button or thumb-nut in 70 the proper direction, so that the brush may be used without the handle, if necessary or desirable.

These securing-nut P may be turned up so tightly as to hold the brush rigidly at any angle to 75 which it may have been adjusted, if it should prove desirable to so hold the brush; or the nut may be so loosened as to permit the brush to swing easily on its pivot-bolt, so that it will accommodate itself to the floor when the 80 latter is being scrubbed. The brush-handle attachment may therefore be changed from a hinged attachment to a rigid attachment, or it may be removed entirely when desirable.

Having described this invention, I claim— 85

The combination, with a brush provided with shouldered plates and a shouldered button on its back, of a handle provided with a hinged disk at its lower end, substantially as specified.

90 In testimony whereof I affix my signature in presence of two witnesses.

GEORGE J. CLINE.
